UNITED STATES PATENT OFFICE.

THOMAS G. PORTMORE, OF SOUTH FRAMINGHAM, MASSACHUSETTS, ASSIGNOR TO DENNISON MANUFACTURING COMPANY, OF SOUTH FRAMINGHAM, MASSACHUSETTS, A CORPORATION OF MASSACHUSETTS.

BAGGAGE AND OTHER CHECK.

No. 922,948.

Specification of Letters Patent. Patented May 25, 1909.

Application filed September 14, 1908. Serial No. 452,904.

To all whom it may concern:

Be it known that I, THOMAS G. PORTMORE, of South Framingham, county of Middlesex, State of Massachusetts, have invented an Improvement in Baggage and other Checks, of which the following is a specification.

This invention relates to baggage and other checks and particularly to consecutively numbered checks composed of two or more integral, separable sections, and identification is made by matching the numbers thereon; and has for its object to provide the sections of the checks with symbols of identification, such for instance as figures, whereby the identification is made by superposition of two sections of the check, without the mind being called upon to recognize the identification symbols, as such. As a result, mental transposition of the identification symbols and other errors due to carrying the identification symbols in the mind are obviated and the attendant loss to the railroad companies reduced.

Figure 1 is a front view of a check embodying this invention, made particularly for use as a baggage check, and Figs. 2 and 3 are modifications to be referred to.

The check herein shown for the purpose of illustrating my invention, is arranged to be used as a baggage check. It comprises two or more integral, separable sections, and in Fig. 1 three sections *a*, *b* and *c* are shown and in the remaining figures only two sections are shown. Each section has printed on it the usual information, such as the name of the railroad company, the date, the place where the check is issued, and the destination of the baggage and such other information as may be desired. When the check is used for other purposes it will have other printed matter thereon. The sections are made of the same width and preferably of the same length, so that when superimposed they will register with each other. Manila, white, or other paper or card-board may be employed in the manufacture of the checks.

Each section has corresponding symbols of identification printed or perforated in large distinct type, as for instance, a number may be employed as the identification symbol. The identification symbol on one of the sections, as *a*, may be printed in black on a red background, see Fig. 1; or in lieu thereof any other two contrasting colors may be em-

ployed; or the identification symbol may be printed in black or other color on a plain manila check, the background being of the color of the paper composing the check, see Fig. 4; or the background may be colored, leaving the number or other identification symbol of the color of the paper composing the check, see Fig. 2; or, as shown in Fig. 3, the number or other identification symbol may be cut in the section like unto a stencil, forming apertures therein, and the background surrounding the apertures left of the color of the paper composing the check, or colored. Whether printed or perforated, the result is the same, in that distinct symbols of identification are produced; and whether the background is colored or left the color of the paper composing the check, the result is the same, in that a distinct contrast between the background and identification symbol is produced.

The section *b*, and if desired the other sections, if more than two sections are employed have corresponding symbols of identification formed by cutting the sections like unto a stencil, apertures being thereby formed in the section. The apertured symbols of identification, which may be a number, correspond in shape and position to the symbols of identification on the section *a*.

The identification numbers may comprise any number of digits, four being herein shown for illustration, but in any event like spaces will be provided on each section for as many digits as the largest number will comprise, and the portions of said spaces which are not used, instead of being left blank, will be filled with any suitable symbols, such for instance, as zeros, see Fig. 1, so that there will be no liability of making a mistake, as for instance, by the placing of 131 on 2131 and assuming that they match. Furthermore, there is liability of confusion unless care is used in the design of the identification symbols, so as to make them of a distinctly different design, particularly if figures such as 3 and 8 or letters such as "c" and "o" are used. For instance, referring to Fig. 1, the figure 3 is of such design that a figure 8 could readily be made in which every part of the figure 3 would be found by merely extending the lines of the 3 to make it form an 8. If this were done and a section having an identification symbol such as 0131 were placed over a section having an identification symbol 0181,

the fact that the identification symbol did not register would not appear. The figures 1 and 4 are similarly liable to confusion. Therefore, all the symbols placed upon the 5 check must be so designed that every symbol when placed over any other symbol used in a series of checks will cause some part of the background surrounding the symbol beneath to show through the perforations.

10 The section *b* or the portion thereof surrounding the apertures may be of the color of the paper composing the check, or it may be of any other color, but ease of identification will be greater if the color differs from 15 the color of the background on section *a*, for instance, if the background on section *a* is red and the section *b* is plain manila, then when the sections are superimposed the failure to register is more readily recognized by 20 the appearance of the red background on section *a* than if the section *b* and the background on section *a* were of the same color.

In the manufacture of the checks if numbers are used for symbols of identification, 25 consecutive numbers will be employed.

When checking baggage or other things, one of the sections will be given to the passenger and the other will be attached to the baggage, and when claiming the baggage the 30 agent will look for a number or other symbol of identification corresponding to the number or symbol of identification on the section which is handed to him, but when completing the identification of the baggage he will 35 place the apertured section *b*, upon the section *a*, to see if the apertures in the section *b* correspond to and register with the symbols of identification on section *a*, and if so correct identification has been made; otherwise 40 not. Thus final identification of the baggage is performed by the eye of the agent, the mind not being called upon to exercise any material function.

Having thus described my invention, what 45 I claim as new and desire to secure by Letters Patent is:—

1. A check comprising two or more sections, one section having symbols of identification and at least one of the other sections 50 having apertures corresponding in shape and position to the aforesaid symbols of identification, so as to register therewith when an apertured section is placed upon the first named section, substantially as described.

55 2. A check comprising two or more sections, one section having a number and at least one of the other sections having apertures corresponding in shape and position to the number on the first named section, so as 60 to register therewith when the sections are superimposed, substantially as described.

3. A check comprising two or more integral separable sections, one section having

printed thereon a number and at least one of the other sections having apertures corresponding in shape and position to the number on the first named section, so as to register therewith when an apertured section is placed upon the printed section, substantially as described. 65

4. A check comprising two or more sections, each section having a space for an identification number composed of a predetermined number of digits, one section having an identification number in the space provided for it and having other symbols of identification arranged to fill said space, and at least one of the other sections having apertures in the space provided for them corresponding in shape and position to the identification number and other symbols of identification on the aforesaid section, so as to register therewith when an apertured section is placed upon the aforesaid section, substantially as described. 70

5. A check comprising two or more sections, one section having thereon figures of distinctly different designs and at least one of the other sections having apertures corresponding in shape and position to said figures, so as to register therewith when an apertured section is placed upon the first named section, substantially as described. 80

6. A check comprising two or more integral separable sections, one section having printed thereon certain figures of a consecutive series of identification symbols and at least one of the other sections having perforated therethrough the same figures of identification symbols, so placed and designed that the perforated symbols will register with the printed symbols when a perforated section is placed upon the printed section and will not appear to register with the printed symbols of the printed section of any other check of the series, substantially as described. 90

7. A check comprising two or more sections, one section having symbols of identification in a background of a contrasting color, and at least one of the other sections having apertures in a background of a color different from the background of the aforesaid section, which correspond in shape and position to the symbols of identification on the aforesaid section, so as to register therewith when said apertured section is placed on the aforesaid section, substantially as described. 105

In testimony whereof, I have signed my name to this specification, in the presence of two subscribing witnesses.

THOMAS G. PORTMORE.
